UNITED STATES PATENT OFFICE.

WILLIAM M. TURNER, OF BELLE UNION, INDIANA.

DEVICE FOR COMMUNICATING MOTION.

SPECIFICATION forming part of Letters Patent No. 243,175, dated June 21, 1881.

Application filed March 28, 1881. (Model.)

To all whom it may concern:

Be it known that I, WILLIAM M. TURNER, of Belle Union, in the county of Putnam and State of Indiana, have invented certain new and useful Improvements in Backlash-Springs; and I do hereby declare that the following is a full, clear, and exact description of the invention, which will enable others skilled in the art to which it appertains to make and use the same, reference being had to the accompanying drawings, which form a part of this specification.

Figure 1 is a side view of my invention. Fig. 2 is a vertical transverse sectional view; and Fig. 3 is a horizontal cross-section on the line $x x$, Figs. 1 and 2.

Corresponding parts in the several figures are denoted by like letters of reference.

This invention relates to an improved method of adjusting cog drive-wheels upon shafts, so that the cogs or teeth shall not, as in starting or stopping, be exposed to any sudden jar or concussion, by which the said cogs or teeth are liable to be broken; and the invention consists in the improved construction and arrangement of parts, which will be hereinafter fully described, and particularly pointed out in the claim.

In the drawings hereto annexed, A represents the shaft or spindle, upon which the main cog-wheel or drive-wheel B is loosely journaled between a collar, C, and a clutch, D, both of which are firmly fixed upon the shaft. The under side of the gear-wheel B is provided with a stud, E, adapted to strike and engage the clutch, or when the motion of the machinery is reversed a stud, F, fixed upon the clutch-collar.

G is a coiled spring, having one end secured to the shaft A, around which it is wound, and having its other end attached to the gear-wheel B, as shown.

H is a wheel or disk, fixed upon shaft A below the gear-wheel B and spring G, and hav-

ing secured to its upper face a series of vertical spring-rods, I, passing through openings or perforations J in a disk, K, vertically adjustable upon shaft A by means of a set-screw, L, and extending through similar perforations M in the gear-wheel B.

From the foregoing description, taken in connection with the drawings hereto annexed, the operation and advantages of my invention will be readily understood.

When power is applied to the shaft the resistance of the spring-rods I and coiled spring G gradually imparts it to the gear-wheel until the clutch D strikes the stud E, thus giving the motion direct to the gear-wheel.

By adjusting the disks H and K upon the shaft the tension of the spring-rods I may be adjusted as circumstances shall require.

It is obvious that this invention is equally well applicable to vertical, horizontal, and slanting shafts, the former being only shown for purposes of illustration.

This invention is simple, durable, and useful, and when once applied is entirely automatic in its operation.

Having thus described my invention, I claim and desire to secure by Letters Patent of the United States—

The combination of the shaft A, gear-wheel B, having stud E and perforations M, collar C, clutch D, having stud F, coiled spring G, disk H, having spring-rods I, and the adjustable disk K, having perforations J, all arranged and operating substantially as herein described, for the purpose shown and specified.

In testimony that I claim the foregoing as my own I have hereto affixed my signature in presence of two witnesses.

WILLIAM MARSHAL TURNER.
